ALBERT M. MARSH, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE

DISINTEGRATING MILL

Application filed March 12, 1928. Serial No. 261,020.

The present invention relates in general to improvements in the art of reducing granular substances, and relates more specifically to improvements in the construction and operation of mills for disintegrating materials such as grain or the like.

An object of the invention is to provide a relatively simple, compact and efficient disintegrating mill especially adapted for the reduction of grain or the like. Another object of the invention is to provide improved apparatus in which granular material may be effectively reduced by the combined action of impact and attrition. A further object of the invention is to provide an improved reduction mill wherein the delivery of material from the source of supply, is automatically checked when the mill stops. Still another object of the invention is to provide improved means for effecting rapid and convenient relative adjustment of the reducing plates of an attrition mill, either for the purpose of regulating the degree of reduction or for the purpose of abnormally separating the plates. A further object of the invention is to provide a motor driven disintegrating mill wherein the reduction surfaces may be relatively adjusted without affecting the operating characteristics of the driving motor. Another object of the invention is to provide a quick release for preventing damaging of the attrition plates of a mill, in case undesirable substances are admitted with the material which is to be disintegrated. Still another object of the invention is to provide an improved reduction mill wherein one of the reducing elements is rotated by means of an electric motor direct connected thereto, and in which the rotary reducing element and the entire motor are simultaneously movable for adjustment purposes. A further object of the invention is to provide improvements in motor mountings especially applicable to attrition mills, and means for effectively dissipating heat created during reduction of the material and for maintaining the driving motor in thoroughly ventilated condition. Another object of the invention is to provide a motor driven disintegrating mill wherein the motor may be located closely adjacent to

the reduction elements so as to form an extremely compact structure, and wherein the product being treated is prevented from reaching the driving motor. These and other objects and advantages of the improvement will appear in the course of the following description.

A clear conception of an embodiment of the invention and of the manner of operating devices constructed in accordance therewith, may be had by referring to the drawing accompanying and forming a part of this specification in which like reference characters designate the same or similar parts in the various views.

Fig. 1 is a top view of an improved motor driven disintegrating mill.

Fig. 2 is a central vertical section through the improved mill.

Fig. 3 is a fragmentary vertical section through the material discharge spout of the improved disintegrating mill.

Fig. 4 is a fragmentary vertical section through another portion of the mill showing the mechanism for assembling, removing and adjusting parts thereof.

The improved disintegrating mill specifically illustrated in the drawing comprises generally a fixed upper attrition plate 5 composed of an annular series of plate sections stationarily mounted in a removable cover 4; a movable lower attrition plate 7 composed of an annular series of plate sections disposed beneath the plate 5 and rigidly attached to a rotary disk 8 within a peripheral retaining lip; a high speed electric motor 11 having a main shaft 10 rotatable about a vertical axis and direct connected to the disk 8 by means of keys and hexagonal clamping nuts 37; and a suitable frame for supporting the motor 11 and the attrition plates 5, 7 and for enclosing these elements.

The supporting and enclosing casing consists of a base 2, an upper casing 3 resting upon and secured to the base 2, and a cover 4 detachably associated with the top of the upper casing 3. The cover 4 is normally rigidly attached to the upper casing 3 by means of a series of clamping screws 29, and is readily removable from the casing 3 when

the clamping screws 29 have been released, by means of jack screws 30 and locking nuts 31 cooperating therewith, see Fig. 4. The jack screws 30 and the nuts 31 are spaced at intervals about the cover 4, and also serve to align the cover 4 and the upper plate 5 associated therewith so that the plates 5, 7 will be disposed parallel to each other and uniform disintegration is insured. The cover 10 is provided with a central feeding eye 6 for introducing material by gravity and for delivering the admitted material upon the irregular nuts 37 and upon the adjacent portions of the rotating disk 8. The upper casting 3 is also provided with a discharge spout 9 as shown in Figs. 1 and 3, for discharging the reduced material from within the reducing chamber 42 formed in the cover 4. Suitable packing means are provided between the 15 top plate of the casing 3 and the hub of the rotor 8 in order to prevent escape of material from the chamber 42 toward the motor 11.

The motor 11 is mounted centrally within the casings 2, 3 by means of a thrust bearing 19 and a series of centering lugs 12 secured to the frame of the motor. The thrust bearing 19 is supported by an adjustable arm 18 one end of which is secured to the base 2 by means of a pivot 20 and the opposite 20 end of which extends freely through an opening in the side wall of the base 2 and rests upon a helical release spring 22 associated with an adjusting rod 21. The adjusting rod 21 has an upper screw threaded end 25 portion which cooperates with an adjusting hand wheel 2 after passing upwardly through a movable bracket 24. A locking hand wheel 26 cooperates with the rod 21 and with the lower end of the movable bracket 30 24, to lock the rod 21 in adjusted position. The hand wheel 23 reacts against the upper end of the bracket 24 and the latter is supported by an eccentric 27 mounted in fixed 35 bearings in a stationary bracket member 25. The eccentric 27 is rotatable by means of a release lever 28 so as to quickly drop the rod 21 and hence the arm 18 and motor 11 together with the disk 8 and plate 7, away from the stationary plate 5, thereby separating the plates 5, 7 and stopping the disintegrating action.

The lugs 12 which are secured to the motor frame are provided with slots within which keys 38 are retained by means of lateral pins and coil springs 13 as shown in Fig. 2. The keys 38 cooperate with keyways 36 formed in the base 2, and adjusting screws 14 cooperate with the springs 13 thereby permitting 40 centering of the motor 11, the disk 8 and the plate 7 relative to the stationary plate 5, from the exterior of the base 2. Partition plates 32, 33 are associated with the lugs 12 and cooperate with internal bores of flanges 45 formed integral with the base 2, to provide

freely vertically slidable partitions which form segregated chambers 39, 40, 41.

Each of the chambers 39, 40 is provided with a fresh air inlet opening 15, and the intermediate chamber 41 is provided with a foul air discharge opening 34. The motor end heads 16, 17 are also provided with air admission openings and the medial portion of the motor frame is provided with an annular series of air delivery openings 35 communicating with the chamber 41. With this arrangement an abundance of fresh air admitted through the inlet openings 15 constantly circulates through the motor end heads 16, 17, and after effectively cooling the motor structure the air is delivered through the openings 35, the chamber 41 and the final discharge opening 34 to the atmosphere.

During normal operation of the improved disintegrating mill, the motor 11 is being operated to produce rapid rotation of the disk 8 and of the lower disintegrating plate 7, the plates 5, 7 having been relatively adjusted to effectively reduce the material advancing therealong. The material requiring reduction is delivered through the feeding eye 6 by gravity, and upon striking the irregular clamping nuts 37 is thrown outwardly against the stationary cover 4 and plate 5 being thus initially broken up by impact. The partially disintegrated material is then urged through the space between the plates 5, 7 by centrifugal force and is thus further reduced by attrition. Due to the extremely high speed of rotation, this speed ordinarily being 3600 R. P. M., the material admitted to and passing through the machine is rapidly reduced and delivered from the periphery of rotating plate 7 by centrifugal force and by the air which is pumped through the attrition space during rotation of the disk 8. The disintegrated material is eventually discharged from the machine through the spout 9 by the fanning action of the rotor and by the air currents set up within the disintegrating chamber 42. The lower surface of the rotating disk 8 also acts to produce a flow of air outwardly therealong, thereby maintaining the lower portion of the chamber 42 free from material and also producing a slight flow of air from the chamber 39 into the chamber 42 thus preventing escape of dust toward the motor 11.

While the motor 11 is in operation, air is drawn into the chambers 39, 40 through the inlet openings 15, and after passing through the motor 11, this air is discharged through the openings 35, the chamber 41 and the final discharge opening 34 to the atmosphere. The air thus circulating through the motor structure maintains the same relatively cool and quickly dissipates the heat created during attrition and transmitted from the plate 7 and disk 8 through the shaft 10 to the motor rotor.

If during normal operation of the machine an undesirably hard piece of material such as metal enters the feeding eye 6, the rotary plate 7 and the disk 8 together with the motor plate 11 will be forced downwardly compressing the spring 22 and thereby permitting the undesirable piece of material to pass through the attrition space without breaking the machine. The space between the plates 5, 7 5 may also be readily adjusted to vary the degree of disintegration, by releasing the locking wheel 26 and by subsequently manipulating the adjusting wheel 23. After adjustment has been effected the locking wheel 26 10 may again be brought into engagement with the movable bracket 24. If it becomes desirable to quickly withdraw the rotary plate 7 from the stationary plate 5, it is only necessary to swing the lever 28 through a predetermined arc thereby causing the plate 7, the disk 8, and the motor 11 to drop by gravity away from the stationary plate 5 a considerable distance proportional to the 15 degree of throw of the eccentric 27. The effective surface of the upper disk 5 may also be brought into proper operative relation 20 relative to the rotating plate 7 by releasing the clamping screws 29 and by manipulating the jack screws 30, the lock nuts 31 serving to lock the jacks in position. The motor 11 and the disk 8 may be properly centered relative 25 to the stationary plate 5 by manipulation of the adjusting screws 14. Sufficient clearance should however be allowed between the plates 30 32, 33 and the adjoining structure, to permit free vertical movement of the motor 11 relative to the base 2.

From the foregoing description it will be apparent that the motor 11 may be located in close proximity to the reduction chamber 42 thereby providing an extremely compact mill, without danger of overheating. The direct connection of the motor to the disk 8 provides an extremely simple and efficient assemblage of elements. The nuts 37 may 40 obviously be provided with additional irregularities in order to enhance the initial impact action, such action being desirable when operating upon caked material, and cooperating with the attrition disks 2 to effectively reduce such material. By admitting the material through a feeding eye 6 above the center of the disk 8, the flow of material is automatically checked when rotation of the disk 8 45 stops. The various adjustments may be made from the exterior of the machine without interfering with the operation thereof, and the plates 5, 7 may be quickly renewed by removing the cover 4. The spring 22 and 50 the quick release device consisting of the lever 28 and eccentric 27, provide safeguards for preventing destruction of the machine. By causing the entire motor 11 to move with the disk 8 and plate 7 during relative adjustment 55 of the plates and during abnormal axial

movement of the lower plate 7, the relative position of the motor rotor and stator, are not affected. The air currents created within the reduction chamber 42 during normal operation of the machine effectively deliver the reduced material and assist in producing a machine of maximum capacity.

It should be understood that it is not desired to limit the invention to the exact details of construction herein shown and described for various modifications within the scope of the claims may occur to persons skilled in the art.

It is claimed and desired to secure by Letters Patent:

1. In combination, a fixed attrition plate, a movable attrition plate cooperating with the underside of said fixed plate, means for feeding material between said plates, a motor having a rotor direct connected to said movable plate for rotating the same about a vertical axis, and means for simultaneously moving said movable plate and the entire motor structure relative to said fixed plate.

2. In combination, a fixed attrition plate, a movable attrition plate cooperating with the underside of said fixed plate, means for feeding material upon said movable plate, means for initially reducing the admitted material by impact and for subsequently further reducing the same by attrition, and means for effecting adjustment of said movable plate relative to said fixed plate.

3. In combination, a fixed attrition plate, a movable attrition plate cooperating with the underside of said fixed plate, means for feeding material through said fixed plate upon said movable plate, means including an adjusting wheel and a rod for effecting vertical adjustment of said movable plate relative to said fixed plate, and means cooperating with said rod but functioning independently of said adjusting wheel for quickly relatively moving said plates away from each other.

4. In combination, a pair of cooperating attrition plates, a motor having a rotor direct connected to one of said plates for rotating the same, said motor being located closely adjacent to said plates, a casing supporting said plates and enclosing said motor to provide a confined space between said motor and said plates, and means for admitting air through said space and said motor to dissipate heat produced during normal functioning of said plates.

5. In combination, a pair of cooperating attrition plates, a motor for rotating one of said plates relative to the other, a casing for supporting said plates and for enclosing said motor, and resilient means associated with said casing for relatively centering said plates by shifting said motor laterally within said casing.

6. In combination, a pair of cooperating

attrition plates, a motor for rotating one of said plates relative to the other, a casing for supporting said plates and said motor, a thrust bearing associated with said casing and coacting with the lower end of said motor for sustaining the weight of said motor and one of said plates, and a guide bearing associated with said casing and coacting with the sides of said motor for maintaining said plates concentric.

7. In combination, a pair of cooperating attrition plates, a motor for rotating one of said plates about a vertical axis, a casing supporting said plates and said motor, a plurality of parallel guideways associated with said casing and coacting directly with the frame of said motor to permit movement of said rotary plate toward and away from the other, and resilient means for centering said motor relative to said guideways.

8. In combination, a pair of cooperating attrition plates, a motor having a rotor direct connected to one of said plates for rotating the same relative to the other, resilient means for restraining bodily movement of said motor longitudinally of its axis of rotation, and resilient means for restraining movement of said motor laterally of said axis.

In testimony whereof, the signature of the inventor is affixed hereto.
